UNITED STATES PATENT OFFICE.

ALFRED HARRY CHURCH, OF LEICESTER, ENGLAND.

MEASURING APPARATUS FOR BOOTMAKERS AND LASTMAKERS.

Application filed January 2, 1924, Serial No. 683,916, and in Great Britain January 8, 1923.

This invention has for its object not only an improved device for measuring human feet for ascertaining requirements for accurate fitting footwear, and for measuring lasts, but it has the great advantages of producing a more efficient apparatus, which is lighter in weight and handier and quicker in use, and very much reducing the cost of production.

10 This invention relates to an improved device for measuring a foot and last in the various important ways from heel to ball-joint, and for measuring round the foot at the ball-joint, the construction being such that when the ball-joint is measured it will indicate what fitting or width of boot or shoe is required. At the same time, a similar device is arranged for measuring the instep, also for measuring the distance from ball-

15 joint to the end of the toes, and at the same time a sliding device is provided which places itself underneath the fore-part of the foot and defines the angle formation of the foot or slope of toes, also showing the exact width

20 of innersole required. Furthermore, in this invention a variable toe-end locator is placed on or attached to the fore-part plates which would prevent at any time the measurement of the foot being taken too short, and also

25 can be used to be brought up against the extreme toe end when a foot is placed upon the machine, not only to assure that the foot does not move forward but in doing so the operator will find that the joint locator will

30 be in very close proximity to the actual ball-joint of the foot and only a slight movement of the ball-joint locator is necessary.

35 The invention will be further described with reference to the accompanying drawings, in which:—

Figure 1 is a longitudinal section;

Figure 2 is a plan view of the complete machine, and

Figure 3 is a cross-sectional elevation on the line II—II of Fig. 2.

In carrying out this invention, a base or casing 1 is provided for mounting the foot-rests, the levers or sliding members which are employed to obtain the correct support of the foot and the required movements. At one end of the base is provided a raised platform 2 to support the heel so that the foot will assume its natural position with the raised heel in readiness to be accurately measured. Suitable means such as heel locators 3 are provided thereon to centralize

the heel and fix the back line from which all lineal measurements of the foot are calculated. Resting on the base 1 and sliding in a slot 4 in the top of the base, are arranged 5, 6, and 7, for locating, indicating and supporting the instep and ball-joint part of the foot, and for carrying a toe-end locating means, respectively. As the lineal expansion or contraction from size to size is greater at the joint than at the instep and is greater at the toe end than at the joint, there is provided a lever 8 having pivotally attached to it at varied distances from the fulcrum 9 of the said lever 8, connecting rods 10, 11 and 12, each of which is attached to its respective slide. This lever and the connecting rods may be for convenience arranged inside the casing or base.

Upon the top of the casing there is provided a pair of levers 13 the ends of which are pivoted at points 14 on the further end of the base 1 removed from the heel support. These levers 13 are referred to as sole and fitting adjustment levers, and have slots 15 in them for a considerable length, and at the ends remote from the pivoted points are pins 16 depending from them. These pins pass through slots 17 in the base 1 of the machine and in combination with a rocking cam 18 at the heel end of the machine the sole and fitting levers 13 are caused to move to and from a centre line of the machine.

Pivotaly attached to the toe-piece slide 7 are a pair of plates 19 and 20 bearing marks *a*, *b* and *c* to indicate angle formation or toe swing, the markings being so arranged that the inside angle formation lines are marked on both plates thus avoiding the reversal of the plates for right or left foot measurements. These plates 19 and 20 have their adjacent corners pivoted at 21 to the toe-slide 7 end and approximately at the opposite end of the plates they have pins 22 arranged to enter into the slots 15 of the long levers 13 known as sole and fitting levers. Moreover, mounted upon the ball joint carriage 6 is a platform 23 to support the sole of the foot to be measured, the platform being mounted in such a way as not to interfere with the ball joint locator or the measuring tapes to be described. The sole and fitting lever adjustment cam 18 above described, is connected to an indicator 25 by a connecting rod 24 which can be mounted inside or outside the base, and the rod may

in co-operation with the indicator 25 be conveniently mounted to read upon a scale 26 marked on or affixed to the base 1 of the apparatus in such a manner as to impart a defined movement of the sole and fitting levers operated by said cam.

As the proportionate sole fitting widths of large sized footwear are naturally greater than the proportionate sole fitting widths 10 of small sized footwear, and as sole and fitting levers 13 are provided with slots 15 in which are engaged the pins 22 controlling the plates 19 and 20 marked with various sole shapes and as the sole and fitting levers 15 13 are narrower at the heel end of the machine and wider at the toe end of the machine, it naturally follows that as the sole width fitting plates are moved backwards or 20 forwards they are caused to separate or approach each other so that the distance between them may always range proportionately according to the position in which they rest.

The ball-joint indicators 6^a are mounted 25 upon a plate or block which can be turned on a pivotal centre 27 so as to obtain the required angle for measuring either the right or left foot. The ball-joint locators requiring to move inwards towards the centre of the sliding ball-joint carriage 6 line or 30 outwards away from said centre yet to retain equal distance from either side, it has been found economical and satisfactory to mount the upright ball-joint locators 6^a each 35 upon a cross bar 28, suitable means, such as a rack 30 on each cross bar 28, said racks cooperating with a pinion wheel 31, being provided to move or adjust the ball-joint locators 6^a to or from the centre equidistantly. Passing through the ball-joint slide 40 or block is a central aperture 32 to accommodate a looped tape the ends of which are secured on the inner-side to a sliding piece 33 guided in a diagonal slot 34 in such a manner that as the joint support block assumes a position of smaller size the take 45 up of the tape is kept proportionate. In a similar manner a tape is passed through the instep support block 5 and in a corresponding manner to the ball-joint tape would take up or let out as the machine contracted or extended in size.

A size scale 35 is provided with a suitable pointer 36 reading thereon which can be taken from any of several parts or movements of the machine. For instance, a size scale can be marked on or affixed to the base 1 of the machine immediately in front of the toe piece carriage 7 and a pointer 36 55 attached to said carriage to give direct reading as to size in any position at which machine is at rest.

A series of indentations such as 39 are 60 provided which are engaged by a spring-catch device 39^a on the toe-piece carriage 7,

which insures that when the toe-piece carriage is moved backwards or forwards, it will come to rest in one of the specified positions.

The operation of the machine is as follows:—

In this case assuming the right foot is about to be measured it is first placed with heel upon heel-rest 2 with back of heel touching upright or heel rest.

The machine can now be quickly moved to convenient size for forepart of foot to rest comfortably on forepart rest table by slight movement of knob or handle 37 attached to toe-plate. Continuing this movement towards the heel would bring the toe-end locators 38 slightly against the end of the toe.

The foot may now be easily centralized by closing in the joint locators 6^a until they 85 lightly engage the foot on either side.

The final adjustment of the joint locators longitudinally is now made either by moving the joint locators themselves or by movements from the knob or handle 37 on toe-plate.

To read off details.

The size is clearly shown on size scale 35 and joint fitting can be read by passing 95 tape over joint. The instep fitting can be read by passing the tape over the instep. The indicating handle or pointer controlling sole and fitting device should now be moved to corresponding letter indicated by 100 joint tape, the operator can then immediately observe by lining up the inside of the foot with the various lines marked upon the forepart plates; or he can observe if a wider or narrower bottom in proportion to circumference is needed.

If the left foot is required to be measured in place of right, it is only necessary to move the bracket carrying the ball joint locator in reverse angle.

I declare that what I claim is:—

1. A measuring apparatus for bootmakers and lastmakers, comprising a base on which is mounted a fixed heel-support, slideable members for locating, indicating and supporting the instep, ball-joint and toes respectively, adapted to slide on top of said base; a lever pivoted at the end of the base remote from the heel-support; connecting-rods pivoted at one end to said lever at various distances from its fulcrum and connected at their other end to the respective sliding members aforesaid; and sole-fitting width indicating means connected to the toe-slide.

2. A measuring apparatus for bootmakers and lastmakers, comprising a base on which is mounted a fixed heel-support, slideable members for locating, indicating and supporting the instep, ball-joint and toes, re-

spectively, adapted to slide on top of said base; a lever pivoted at the end of the base remote from the heel-support; connecting-
 rods pivoted at one end to said lever at various
 5 distances from its fulcrum and connected at their other end to the respective sliding members aforesaid, and sole-fitting width indicating means comprising an indicator to indicate the fitting or width of foot-
 10 wear required, a slotted rocking-plate connected to said indicator, a pair of levers pivoted at one end to the base at a point remote from the heel-support and at their other end having a pin and slot connection
 15 with said slotted rocking-plate, and a pair of plates pivoted to the toe-slide and having a pin and slot connection with said pair of levers.

3. A measuring-apparatus for bootmakers and lastmakers, comprising a base provided with a slot and on which is mounted a fixed heel-support, slidable members for locating, indicating and supporting the instep, ball-joint and toes respectively, adapted to slide 20 in said slot, a central plate pivotally connected to said ball-joint member, laterally movable ball-joint locators mounted on said central plate; a lever pivoted at the end of the base remote from the heel-support, connecting-rods pivoted at one end to said lever at various distances from its fulcrum and connected at their other end to the respective sliding members aforesaid; and sole-fitting width indicating-means connected 25 to the toe-slide.

4. A measuring apparatus for bootmakers and lastmakers, comprising a base provided with a slot and on which is mounted a fixed heel-support, slidable members for locating, indicating and supporting the instep, ball-joint and toes respectively, adapted to slide 30 in said slot; laterally movable ball-joint locators simultaneously adjustable equidistantly from the center of the slidable member for the ball-joint; a lever pivoted at the end of the base remote from the heel-support, connecting-rods pivoted at one end to said lever at various distances from its fulcrum and connected at their other end 35 to the respective sliding members aforesaid; and sole-fitting width indicating means connected to the toe-slide.

5. A measuring apparatus for bootmakers and lastmakers comprising a base provided 40 with a slot and on which is mounted a fixed heel-support, sliding carriages for locating, indicating and supporting the instep, ball-joint and toes respectively, adapted to slide in said slot, the ball-joint and instep carriages 45 each having a central aperture, a looped

measuring tape arranged in each aperture, a sliding piece to which the two ends of the measuring tape are secured, a guide member extending in a direction longitudinally of the base and disposed at an angle with 55 respect to the planes of the top and bottom of said base, said sliding piece being guided in said angularly disposed guide-member so that the take-up of the measuring-tape may be proportionate to the sizes measured, a lever pivoted at the end of the base remote from the heel-support, connecting rods pivoted at one end to said lever at various 60 distances from its fulcrum and connected at their other end to the respective sliding members aforesaid; and sole-fitting width indicating means connected to the toe-slide.

6. A measuring apparatus for bootmakers and lastmakers comprising a base on which is mounted a fixed heel-support; slidable 80 members for locating, indicating and supporting the instep, ball-joint and toes respectively, adapted to slide on top of said base; a lever pivoted at the end of the base remote from the heel-support; connecting-rods pivoted at one end to said lever at various 85 distances from its fulcrum and connected at their other end to the respective sliding members aforesaid; and sole-fitting width indicating means comprising an indicator 90 to indicate the fitting or width of footwear required, a slotted rocking-plate connected to said indicator, a pair of levers pivoted at one end to the base at a point remote from the heel-support and at their other end having a pin and slot connection with said pair of levers, 95 said pair of plates having upright plates thereon serving as toe-end locators.

7. A measuring apparatus for bootmakers and lastmakers comprising a base on which is mounted a fixed heel-support; slidable members for locating, indicating and supporting the instep, ball-joint and toes respectively, adapted to slide on top of said base, a lever pivoted at the end of the base remote from the heel-support; connecting-rods pivoted at one end to said lever at various 100 distances from its fulcrum and connected at their other end to the respective sliding members aforesaid; sole-fitting width indicating-means connected to the toe-slide; and a size-scale on the base and a pointer on 105 the toe-slide to give direct readings as to size.

In witness whereof, I have hereunto signed my name this 10 day of December 110 1923.

ALFRED HARRY CHURCH.
